WALLET

Frederick Brunskill, Liverpool, England

Application September 21, 1937, Serial No. 164,929
In Great Britain September 19, 1936

4 Claims. (Cl. 150—38)

This invention is for improvements in or relating to apparatus for feeding a sheet or sheets into and/or out of a pouch, the term sheet or sheets where used in this specification including 5 cards, thin boards, a mirror or the like. The invention is particularly concerned with an apparatus for delivering sheets of, for example, paper from a stack contained in a pouch. One particular application of the invention is to wallets and pocket books but it will be appreciated that the invention may be applied for delivering sheets of paper such as circulars or envelopes or the like from a stack contained in other forms of pouch or pocket.

15 According to one feature of the present invention there is provided an apparatus for feeding sheets or the like into and/or out of a pouch (e. g. a wallet) comprising sheet-engaging means adapted to be supported in or on the pouch for 20 movement relatively to the aperture thereof and means for moving said sheet engaging means to feed one or more sheets through the pouch aperture. Conveniently the sheet-engaging means comprises a friction roller rotatably supported 25 within the pouch and having an operating spindle by which it can be rotated to feed one or more sheets through the pouch aperture. In applying the invention to a pouch such as a wallet the apparatus may comprise a partition sheet built 30 into the pouch between the walls thereof and apertured and provided with bearings for rotatably supporting a friction roller in said aperture, a friction roller mounted on a spindle journaled in said bearings and projecting through the wall 35 of the pouch whereby the roller can be rotated from the exterior of the pouch selectively to feed sheets located on opposite sides of the partition sheet through the pouch aperture according to the direction in which the roller is rotated.

40 The invention will be further described with reference to the accompanying drawing which shows several examples of a wallet including a note feeding device constructed according to the invention.

45 On the drawing—

Figure 1 is a front elevation of a wallet of the kind adapted to be folded about its vertical centre line, the wallet being shown in its open or unfolded position and partly broken away to show 50 the note feeding device.

Figure 2 is a plan view of Figure 1.

Figure 3 is a fragmentary cross-section on the line III—III of Figure 1.

Referring to the embodiment of the invention 55 shown in Figures 1, 2 and 3, the wallet which

may be constructed of leather or the like comprises a front sheet 10 and a back sheet 11 stitched together at the sides 12 and 13 and at the bottom 14 to form a pocket 15 of a size adapted to receive Treasury notes. Additional sheets of material 16 and 17 are stitched to the front sheet 10 to provide pockets for containing stamps or the like. For compactness the wallet is adapted to be folded about its vertical centre line 18.

The note feeding device comprises a flexible 10 partition sheet 19 of leather or the like stitched into the side 13 of the wallet and the bottom 14 thereof and adapted partly to divide the pocket 15 into two compartments 20 and 21 in which Treasury notes of different denominations can 15 be located. The Treasury notes in the compartments 20 and 21 are adapted to be delivered selectively therefrom by a knurled friction roller 22 of vulcanized rubber or the like fitted on a spindle 23 journaled in bearings 24 and 25 which 20 are formed by stitching strips of material 26 on one side of the partition sheet 19 which is apertured at 27 so that the roller 22 projects through the sheet on either side thereof. The roller 22 is adapted to be rotated by a knurled knob or 25 finger piece 28 which is fitted on the outer end of the spindle 23 and is accommodated in a cut-away recess 29 in the side edge 13 of the wallet.

When a note is required from the pocket book, the knurled knob 28 is gripped between the finger 30 and thumb and turned in one or other direction according to the denomination of note required and the roller 22 will engage the note with which it is in contact and deliver it through the open 35 top of the wallet the notes on the opposite side 35 of the sheet 19, being retained in the wallet. The roller has a tendency to separate the notes, thereby facilitating the selection of a single note from the wallet. To ensure that the friction between the roller 27 and the notes is sufficient to feed a 40 note through the aperture of the pocket book, the wallet may be held so that the finger and thumb apply a slight pressure thereto at points at opposite sides of the roller.

In applying the embodiment of the invention 45 above described to wallets which are not adapted to be folded about their vertical centre line, the shaft 24 may extend from one side of the wallet to the other and a knurled knob may be provided on both ends thereof, or the shaft may be made 50 of flexible material so that it will bend freely and permit the wallet to be folded. For example the shaft may be made of wire or the like plated to give a good appearance and reduce the friction at the bearings. 55

Whilst the invention has been described more particularly as applied to a device for delivering notes from a wallet it is to be understood that it may also be used for feeding notes into a wallet 5 after their lower edge has been introduced into the mouth thereof, the embodiment of the invention shown in Figures 1, 2 and 3 being suitable for either purpose.

One of the advantages of the invention is that 10 it tends to eliminate the risk of two Treasury notes being extracted from a note case instead of one note, the friction roller having a tendency to separate the note in immediate contact with it from the other notes.

15 The note engaging means may comprise a device other than a roller, and where a roller is used such roller may be connected to its operating knob through gearing so that a comparatively small angular movement of the knob will result 20 in several revolutions of the roller shaft thereby providing a quick delivery of the appropriate sheet of material.

I claim:

1. A wallet having walls including a partition 25 sheet built into the wallet between the walls thereof to divide the wallet into two pockets, said partition sheet having an aperture, a friction roller located in said aperture whereby it is operative to engage sheets located in both of said 30 pockets, a spindle for said friction roller and bearings on the partition sheet for said spindle, the spindle having a part extending outside the wallet whereby the roller can be rotated from the exterior of the wallet selectively to deliver 35 sheets from either pocket thereof according to the direction in which the roller is rotated.

2. A wallet having walls secured together at 40 their side edges and bottom edge and open at their top edge, including a partition sheet secured at one edge and at the bottom by the 45 securing means at these parts for the walls, said partition extending otherwise free of the connection with the walls and between the walls of the wallet to divide the wallet into two pockets, said partition sheet having an aperture, a friction roller located in said aperture whereby it is operative to engage sheets located in both of said pockets, a spindle for said roller and bearings on the partition sheet for said spindle, said spindle having a part extending outside the wallet through the side edge thereof, said side 50 edge having a recess adjacent the extending part of the spindle and said spindle having a finger grip accommodated in said recess whereby the roller can be rotated from the exterior of the wallet selectively to deliver sheets from either pocket thereof according to the direction in which the roller is rotated.

finger grip accommodated in said recess, whereby the roller can be rotated from the exterior of the wallet selectively to deliver sheets from either pocket thereof according to the direction in which the roller is rotated.

3. A wallet in the form of a pocket book having walls secured at their side edges and bottom edge and having a formed line of fold intermediate the side edges to permit the pocketbook to be folded about a vertical center line 10 and having a partition sheet attached to the wallet by the securing means uniting the walls at one side edge and the bottom edge and extending inwardly between the walls of the pocketbook in an otherwise unconnected relation, the free end of the partition extending past the vertical line of fold of the pocketbook, whereby the partition sheet serves partly to divide the wallet into two pockets, the said partition having an aperture, a friction roller located in 15 said aperture whereby it is operative to engage sheets located in both of said pockets, a spindle for said friction roller and bearings on the partition sheet for said spindle, the spindle having a part extending outside the wallet whereby the 20 roller can be rotated from the exterior of the wallet selectively to deliver sheets from either pocket thereof according to the direction in which the roller is rotated.

4. A wallet in the form of a pocket book having walls adapted to be folded about a vertical center line and having a partition sheet stitched to the wallet between the edges of the walls thereof at one side of the wallet and terminating adjacent said center line whereby the partition sheet serves partly to divide the wallet into two pockets, said partition sheet having an aperture, a friction roller located in said apertures whereby it is operative to engage sheets located in both of said pockets, a spindle for said roller, strips 40 of material secured to the partition sheet on opposite sides of the aperture therein and embracing said spindle to form bearings therefor, said spindle having a part extending outside the wallet through the side edge thereof, said side 45 edge having a recess adjacent the extending part of the spindle and said spindle having a finger grip accommodated in said recess whereby the roller can be rotated from the exterior of the wallet selectively to deliver sheets from either 50 pocket thereof according to the direction in which the roller is rotated.

FREDERICK BRUNSKILL.
